VARIABLE ROCK FURNACE WORKING

Claude M. Weinheimer, Frank P. Weaver, and Leon V. Pittman, Detroit, Mich., assignors, by mesne assignments, to Kuhlman Electric Company, Bay City, Mich., a corporation of Michigan

Application January 16, 1935, Serial No. 1,994

9 Claims. (Cl. 13—34)

The present invention relates in general to a furnace of the electric type for the melting of metals, and is more particularly concerned with improvements in the working of furnaces of the type wherein the melting chamber is rocked during the melting operation.

Heretofore, it has been common practice to melt metal in a furnace which was so arranged that the melting chamber could be rocked or oscillated to cause agitation of the metal during the melting operation. Such apparatus as a rule made provision for varying the amount of rock or agitation of the metal, but the amount of agitation and its variation was left largely to the discretion of the operator, and varied with different types of metals and alloys.

We have now discovered that there are other factors, heretofore not appreciated, in the agitation of metal which is being melted which contribute in a large degree to the speed and efficiency with which the metal may be melted or reduced.

More specifically, it has been discovered that there is a direct relationship between the speed or rate of melting of the metal and the rate of increase in the amount of agitation or rocking, which if adhered to will result in the most efficient melting of the metal. That is, the metal as it begins to melt should be agitated gently and then as the melting progresses, the agitation may correspondingly be increased until the maximum agitation is reached when the metal becomes completely melted.

Having the foregoing in mind, the present invention contemplates as its primary object an improved method of melting metal, wherein advantage may be taken of our discovery to effect efficient and rapid melting of the metal.

In accordance with the general features of the invention, the rocking mechanism for practicing the steps of our invention embodies a motor driven crank shaft having eccentrically supported thereon a crank pin. This crank pin is mounted on a revolvable member which may be revolved by means of a worm arrangement so that the crank pin may be disposed at variable distances from the center line of the crank shaft, whereby the throw of the crank may be altered to increase the rocking motion of the furnace. The motion of the crank pin is transmitted to a link and gear arrangement, the gearing being positively connected to the furnace shell.

Associated with the rocking mechanism is a striking lug arrangement which is in the path of a feed wheel for turning the worm a specific

amount each time the crank makes a revolution. With this feature, the rock may be automatically increased from a minimum value to a large value without the necessity of control by the furnace operator. In order to terminate the rocking increase when a predetermined maximum value is reached, the striking lug is arranged to be kicked out automatically, whereby the furnace will continue to rock at a maximum angle until the rocking mechanism is shut down.

Other objects and features of this invention will more fully appear from the following detailed description taken in connection with the accompanying drawings which illustrate a single embodiment thereof, and in which:

Figure 1 is a view in elevation of a furnace apparatus which may be operated according to the principles of the present invention, portions being cut out to disclose details of the melting chamber shell structure;

Figure 2 is an end view of the furnace, portions of the shell of the melting chamber being broken away to show details of the charging door;

Figure 3 is an enlarged fragmentary view having sectional portions taken substantially on line III—III of Figure 1 to show details of the rocking mechanism;

Figure 4 is an enlarged fragmentary view partly in section and having portions of the melting chamber shell broken away to show details of the rocking mechanism, taken substantially on line IV—IV of Figure 3;

Figure 5 is an enlarged sectional view through the electrode supporting and feeding mechanism, taken substantially on line V—V of Figure 1;

Figure 6 is an enlarged fragmentary section through the charging door and associated shell, taken substantially on line VI—VI of Figure 1;

Figure 7 is a sectional view through the driving crank of the rocking mechanism, taken substantially on line VII—VII of Figure 3; and

Figure 8 is a fragmentary sectional view of an alternative crank arrangement to enable reducing the rocking motion to a zero value.

Figure 9 is a sectional view on line IX—IX of Figure 2, to show details of the striker pin.

As shown on the drawings:

In the illustrated embodiment of the invention, there is shown in Figure 1 an electric furnace of the rocking type which is so arranged that the metal which is being melted may be agitated by rocking the furnace back and forth.

This furnace comprises a supporting structure which is generally indicated at 10. This structure is provided with a plurality of wheels 11 which are

arranged to provide a four-point rolling support for a substantially cylindrical shell 12 which defines the melting chamber. The two wheels at the forward side of the furnace are each rotatably mounted on a spindle 13 which is secured in the supporting structure. The inner edge of each wheel is deflected to form a peripheral flange 14. The spindle 13 is provided with a longitudinal passage 15 which is arranged so that the wheels may be pressure lubricated.

At the rear side of the shell 12, as shown in Figure 4, the wheels 11 are of similar construction, but instead of being mounted for free rotation, they are secured to a shaft 16 having its ends supported for rotation in anti-friction bearings 17-17. At either end of the shell 12 is a rail or track 18 which engages the wheels 11 at the associated end of the shell.

In the prior art devices of the herein described character, these rails were attached by brackets directly to the outer surface of the shell 12 and were subject to undesirable forces tending to cause distortion of the rails as a result of the radial expansion of the shell. In order to provide a more economical construction and overcome the foregoing objection, the shell 12 is, in this instance, closed at each end by an end member 19 which is peripherally extended and deflected to form a peripheral flange which extends over the end of the shell 12 and defines the aforementioned track or rail 18. Each end is secured in position to the shell 12 by means of a plurality of circumferentially spaced bolts 20 which are welded at their inner ends to the shell and are adapted at their outer ends for receiving securing nuts 21. Since the end member and shell are substantially co-radial, they will expand and contract together during temperature changes whereby undesirable stresses will be substantially eliminated.

In the operation of furnaces of this character, it has been found advantageous to provide a positive connection between the shell and the rocking mechanism, rather than to depend entirely upon the frictional engagement between the driving wheels 11 on the shaft 16. For this purpose, one of the end members 19, in this instance the end member at the right end of the shell 12, as viewed in Figure 1, is provided at its periphery with circumferentially extending teeth 22 which define a relatively large gear 23. The teeth of the gear 23 mesh with the teeth of a pinion 24 which is mounted on and rotatable with the driving shaft 16. It will now be evident that if the shaft 16 is rotated in one direction, the furnace shell 12 will rotate or rock in one direction, and reverse its direction of rock when the rotation of the shaft 16 is reversed.

For oscillating the shaft 16, a novel rocking mechanism is provided. An electric motor 25 has its driving shaft connected to suitable reduction gears contained in a gear casing 26, power being delivered through a delivery shaft 27. The outer end of the shaft 27 carries an adjustable throw crank generally indicated at 28. This crank comprises a ring-shaped housing 29 having a substantially tangential cylindrical portion 30. The ring 29 is provided at one edge with an inwardly deflected portion defining a flange 31 which cooperates with a groove 32 which extends circumferentially around the peripheral surface of a worm wheel 33, whereby the worm wheel is rotatably mounted in the housing. Rotation of the worm wheel is accomplished by means of a worm 34 which meshes with the teeth of the worm

wheel. The worm 34 is formed on a shaft 35 which is rotatably mounted in the cylindrical portion 30 of the housing, one end of this shaft extending to the exterior of the housing and being provided with an actuating sprocket wheel 36, the purpose of which will be subsequently more fully explained.

Outwardly disposed from the center of rotation of the worm wheel 33 is a crank pin 37. On the opposite side of the housing 29 from the location of the crank pin 37, the housing is provided with a cover 38 which is secured at its periphery to the housing 29 by means of screws 39. The housing 29 is eccentrically supported relative to the shaft 37 by means of a hub 40 which is integrally formed in the cover 38 and is secured to the shaft 27 by means of a set screw 41.

With the foregoing arrangement, it will be apparent that the throw of the crank may be adjusted to a large or small value by revolving the crank pin 37 by means of the worm and worm wheel about a circular path having its axis offset relative to the axis of the shaft 27. In the arrangement disclosed in Figure 7, the radius of rotation of the crank pin 37 is such that the throw of the crank may be varied from a minimum value to a maximum value, the minimum value being in this case greater than zero.

The invention, however, contemplates that there may be cases when it is desired to have the minimum throw zero and increase the throw from zero to a maximum value. In Figure 8, an alternative arrangement is shown to meet such a requirement. In this construction, it is only necessary to choose the radius of revolution for the crank pin of such a value as to permit the crank pin axis and the shaft 27 axis to be brought into coincident relationship by actuating the worm and worm wheel. In Figure 8, the corresponding parts have been indicated by similar numerals as utilized for like parts in Figure 7.

A connecting link, generally indicated at 42, transmits the movement of the crank pin 37 to a rotatably mounted crank arm 43 which is secured to and movable with a segmental gear 44. The teeth on this gear mesh with a pinion 45 which, together with a gear 46, is rigidly secured to a short shaft 47 having its ends mounted in anti-friction bearings 48-48, these bearings being suitably supported in an enclosing casing 49 and cover plate 50 therefor. The cover plate 50 is secured to the casing by means of a plurality of screws 51. The gear 46 meshes with a pinion 52 which is secured to one end of the shaft 16.

The amount of rocking is automatically increased from a minimum or zero value to a maximum value by progressively advancing or turning the worm 34 a predetermined amount during each revolution of the crank pin 37. This is accomplished by means of a striker lug or pin which is disposed in the line of travel of the sprocket 36. The striker lug or pin comprises a bracket plate 53 which is secured as by bolts 54 to the frame structure. At one edge of this plate and normal to the surface thereof, there is integrally formed a tubular bore 55 within which there is mounted a piston-like member 56 which is axially slidable in the bore. A stem 57 projects outwardly from one end of the member 56 and has secured at its outermost end a cap 58 having a cylindrical body 59 which is outwardly spaced relative to the stem 57 and forms a housing for a compression spring 60 which surrounds the stem. One end of this spring bears against the closed end of the cap 58.

and the other end of the spring bears against the portion of the housing forming the adjacent end of the bore 55.

The surface of the member 56 adjacent its stem end is provided with a pair of transversely extending and opposed parallel grooves 61—61 of substantially V-shape, these grooves defining dwell points for receiving the chisel-like ends of associated detent pins 62—62 which are in each case axially forced into the associated groove by an expansion spring 63.

The member 56 is also provided with a pair of flat inclined surfaces 63' which extend away from the grooves 61—61 and converge towards the opposite end of the member 56 to form a contracted portion defining the dwells 64—64, the purpose of which will subsequently be evident.

This latter end of the member 56 is extended to form a web portion 65 having its outer end rounded as shown at 66. One side of this web carries a normally disposed rib 67 which extends longitudinally along the web. The other side of the web, as shown in Figure 9, is provided with a similarly disposed rib 67' which projects outwardly from the web an amount slightly greater than that of the rib 67.

With the rib 67 disposed as shown in Figure 3, it will engage the teeth on the sprocket wheel 36 each time the crank is revolved, and will advance the sprocket wheel, for example, one tooth during each revolution of the crank. The angle of rock will therefore be slowly increased in steps until a maximum angle is reached, at which time the pivotal connection of the link 42 to the crank pin 37 will strike the curved end 66 of the web 65 and move the member 56 to the right, thereby disengaging the detent pins 62 from the grooves 61—61. The spring 60 continues to force the member 56 outwardly until the detent pins 62—62 come to rest in the dwells 64—64.

Should it be desired to advance the rocking angle more rapidly, the cap 58 is rotated through an angle of 180 degrees, which action will bring the rib 67' into the position formerly occupied by the rib 67. Since the rib 67' projects a greater amount than the rib 67, it will engage the sprocket wheel one tooth ahead of the position engaged by the rib 67 and will therefore advance the sprocket wheel two teeth each time the crank makes one revolution. It will be obvious that when the maximum rocking angle is reached and the striking pin has been kicked out, the furnace shell will continue to rock at the maximum angle until the rocking mechanism has been shut down.

Referring to Figures 1 and 6, it will be observed that the furnace shell 12 is provided with a charging and pouring door which comprises an oval-shaped frame member 68 which is secured to the shell 12 by means of a plurality of bolts 69. The charging door comprises an oval-shaped plate 70 having hook hinge lugs 71—71 at its upper edge which cooperate with hinge pivot members 72—72 on the frame 68. The charging door, being thus hinged, may be swung upwardly by means of a handle 73 adjacent its hinged upper edge and easily removed, when desired.

As shown in Figure 6, the charging door has a lining of refractory material 74 on its rear surface, this lining being secured to the door proper by means of suitable bolt and nut connections 75—75. The charging door may be clamped in closed position by means of a pair of laterally positioned screws 76—76 which are each thread-

ed into a yoke 77 having its end portions pivoted at 78 for swinging movement. During the clamping operation, the screws 76 respectively engage laterally extending lugs 79 which are integrally formed with the door. When it is desired to open the door, the screws 76 may be loosened and the yoke 77 swung outwardly so as to release the lug portions 79 and enable the door to be swung open or removed.

Referring to Figures 1 and 2, it will be observed that the lower edge of the door 70 is provided with an arcuate cut-out portion 80 which cooperates with a metallic member 81, this latter member being so shaped as to form a pouring spout which is lined with clay in a manner well known in the art.

In order that the metal, when being poured, may be kept out of contact with the air during its movement from the furnace to the ladle or mold, a tubular conductor 82 is supported by a suitable bracket 83 with one end secured in the pouring opening below the door proper. The use of the pouring conductor just described prevents oxidation of the metal during the pouring operation. In order that further control of the atmospheric conditions surrounding the melting or reduction of the metal may be effected, the furnace shell is provided with an opening as shown at 84, this opening being adapted in any well known manner for making a flexible pipe connection thereto. It is preferred that this opening be disposed within the angle subtending the arc of the shell occupied by the charging door, so that this opening will not be washed by the molten metal during the rocking operation.

By connecting a flexible pipe and using suitable valve controls, it is possible to conduct carbon monoxide, carbon dioxide, or other fluid mediums into the furnace shell, and thus control the reducing atmosphere during the melting and pouring operations.

In the herein described embodiment of the invention, it is proposed to manually shift the furnace during the pouring of the molten metal. This is accomplished by providing a socket member 85 on one of the end members of the shell 12, the socket member being adapted to receive therein a removable lever 86 by means of which the shell may be manually rotated to such position as to permit the molten metal to flow through the tubular conductor 82. This manual pouring would necessitate a reversal of the operation of the rocking mechanism, and since it would be impractical to reverse the gears, etc., it has been found desirable to provide means for disconnecting the major portion of the rocking mechanism during the pouring operation.

The foregoing is accomplished by making the connecting link 42 in two parts, namely, a tubular sheath 87 which is fixedly secured as by a pin 88 to a pivot bearing 89 which is associated with the crank 43, and a shaft member 90 which is slidably within the sheath 87 and is connected at one end to a pivot bearing 91 which is associated with the crank pin 37. The tubular sheath 87 and shaft 90 are normally locked together by means of a manually operable spring actuated lock comprising a cylindrical member 92 which extends normally to and is fixedly secured to the sheath 87.

Within the tubular member 92 there is mounted for reciprocable movement a pin or plug member 93 having a tapered end portion 94 which is adapted to extend through an opening in the sheath 87 into an opening 95 in the shaft 90. For

actuating the pin 93, a stem 96 is secured thereto, this stem extending through a plug 97 in the open end of the tubular member 92 and having at its upper end a button 98 which may be grasped by the operator's fingers and pulled upwardly to free the sheath 87 and shaft 90 for relative axial movement. The latching pin 93 is normally forced in a downward direction by means of a compression spring 99, one end of which bears against the pin 93 and the other end against the plug or bushing 97.

It will therefore be evident from the foregoing description that if the latch just described is released by pulling up on the same, the operator may by means of the lever 86 rotate the furnace to the pouring position. This movement of the furnace will likewise cause a movement of the crank arm 43 and will cause the connecting link 42 to be telescopically elongated, without the necessity of having to rotate the crank pin 37 and its connections to the motor mechanism. As soon as the pouring operation is completed and the furnace is rotated in the opposite direction the latch plug will automatically engage the shaft 90 and re-establish a rigid link connection between the crank pin 37 and the crank arm 43.

A pair of electrodes are supported on the end members of the furnace shell, the axes of the electrodes being coincident with the shell axis. Each electrode is provided with its individual feeding mechanism which permits the electrode to be axially fed into the melting chamber.

Referring to Figure 1, it will be seen that the associated end member 19 is provided with an outwardly extending ring flange 100 for receiving therethrough an electrode 101, suitable bushing members 102 and 103 being disposed between the electrode and the flange 100, whereby the electrode is insulated relative to the furnace shell structure.

The electrode supporting and feeding mechanism comprises a U-shaped bracket generally indicated by the numeral 104. The spaced legs of this bracket 105 and 106, respectively, are outwardly deflected at 107 and 108 to form securing feet or lugs which are secured to the associated end member 19 as by securing bolts 109. Adjacent the feet 107 and 108, the spaced legs of the bracket are interconnected by a bridging member 110 which not only braces the legs of the bracket but also serves as an inner bearing for an upper guide rail 111 and a combination lower guide and screw 112, the outer ends of these guide members being rotatably supported in the closed end of the bracket. Actuation of the combined guide and screw 112 is accomplished by means of a suitable hand wheel 113.

Associated with the guide rail 111 is a guide block 114, and with the guide screw 112 a nut block 115. The blocks 114 and 115 are clamping secured as by through bolts 116 to a hollow clamping member 117, the blocks in each case being insulated from this member 117 by means of insulating members 118 and 119, respectively. One face of the hollow clamping member 117 is provided with an inwardly deflected portion 120 defining a semi-circular surface for engaging with the electrode. Cooperatively associated with the clamping member 117 is a hinged clamping member 121 which is pivoted at 122 to the block 117 and is provided with a recessed portion 123 which defines a semi-circular surface for engaging the electrode. The upper edge of the clamping member 121 is provided with an open-ended slot 124 for receiving therein a hinged bolt 125 that is

pivoted at its inner end 126 for swinging movement and threaded for cooperation with a hand nut 127.

The hollow clamping member 117 is provided with threaded lateral openings 128 and 129 for connection to suitable fluid inlet and outlet connection, whereby a cooling fluid may be circulated through the hollow clamping member. The rear wall of the hollow clamping member is provided with an integrally formed extension 130 having a right angled flange portion 130' with a plurality of holes 131' therethrough to facilitate the bolting of electric power supply cables to the hollow clamping member. The closed end of the bracket 104 has secured thereto a plate member 131 by means of bolts 132, which is adapted to support an insulated guide bushing 133 for receiving therethrough the electrical power supply cables.

With reference to the manner in which the power supply cables and water connections were brought to the electrode clamps in the prior art devices of the herein described invention, it was customary to carry the cables in a loop from a stationary bus bar at the back of the furnace to the guide bushing 133 and also provide a loop between the guide bushing and the connection at the electrode. This arrangement proved objectionable in that the cables were subjected to bending forces during the rocking of the furnace and were subject to breakage at the point where they passed through the guide bushing.

The foregoing objections and difficulties have been overcome by the arrangement shown in Figure 1, wherein the cables and fluid connections at each end of the furnace are held stationary at a point near the axis of rocking and are carried in a relatively short single loop to the guide bushing at that end so that the effect of the rocking movement of the furnace on the cables and fluid connections is absorbed by a twisting rather than a bending motion.

As disclosed, the electric power supply cables 134 are carried through a suitable conduit 135 to a junction or outlet box 136 which is supported at or near the rocking axis of the furnace. Cooling fluid supply and return pipes 137 and 138 respectively are provided adjacent the outlet box and hose connections 139 and 140 carried through suitable openings into the junction box 136, a suitable control valve 141 being placed in the supply pipe. From the junction box the cables and hose connections are grouped by a rubber band or the like 142 and carried in a loop to the guide bushing 133, and thence to the electrode clamp where appropriate connections are made, as hereinbefore described.

Referring to Figure 2, it will be noted that the electrode bracket 104 is offset relative to the diameter of the furnace shell and is disposed on the opposite side of this diameter from the location of the charging door. With this arrangement, the weight of the charging door and its tendency to rotate the furnace during the pouring operation is counterbalanced.

In operation, the means embodied in the herein described invention for varying the angle of rock automatically during the operation is of particular advantage in that it enables the rocking angle to be initially increased at relatively small increments over a succession of uniformly spaced intervals of time. These increments, due to the inherent construction of the mechanism for adjusting the throw of the crank, are increased as the maximum rocking angle is approached. Such

operation has proved to be very desirable in a furnace of this type.

The advantages of this method of operation will become more evident from a brief consideration 5 of the melting operation.

In a furnace of the herein described type, it is desirable to wash the refractory with molten metal in order to keep the temperature of the refractory relatively low and, moreover, due to 10 the heat absorbed by the molten charge from the refractory during the rocking operation, it is desirable to decrease the rate at which the metal is heated, thereby reducing the electrical operating costs.

15 It will be apparent that full rocking cannot immediately be employed as soon as the furnace is started, since the tumbling action of the solid pieces composing the charge might injure the electrodes and possibly the refractory. Moreover, 20 with the charge in solid form, the transfer of heat from the hot refractory to the charge would be relatively low due to the small contact area between the charge pieces and the refractory.

As the heating proceeds, some of the charge 25 pieces will be melted and fall through the interstices of the other pieces to the bottom of the melting chamber. This molten metal may be washed back and forth through a small arc, but should not be agitated too vigorously since by doing so the remaining solid pieces might injure the refractory or electrodes.

The variable rock feature of the present invention is therefore decidedly advantageous in that it permits the angle of rock to be increased at 35 substantially the same rate as the metal is being melted down below the electrodes.

The striker lug as previously described may be set to automatically advance the rocking angle in a relatively slow or rapid manner, as desired. 40 This feature enables adjustment of the rate of increase of the rocking angle for metals having different melting rates. For example, brass melting would require a faster rate of increase in the rocking angle than would iron.

45 From the foregoing description it will be apparent that the herein-described invention provides an improved method for the melting of metal, wherein the amount of agitation of the metal is varied as a function of the rate of increase of the melted metal, the agitation being such as to gently agitate the metal as it begins to melt, and thereafter being increased to a maximum as the rate of melting increases, a maximum of agitation being reached when the 50 metal becomes completely melted, whereby the metal is more efficiently and rapidly melted.

Now, of course, it is to be understood that while the invention is illustrated and described in de-

tail in its preferred form, the invention is not to be thus limited but only insofar as defined by the scope and spirit of the appended claims.

We claim as our invention:

1. The method of melting a metal in a furnace 5 of the rocking type which consists in increasing the amount of rock at substantially the same rate as the rate at which the metal therein is being melted.

2. The method of melting a metal in a furnace 10 of the rocking type which consists in varying the amount of rock as a function of the speed at which the metal is melted.

3. The method of melting a metal which consists in agitating the metal to be melted, and the 15 varying of the amount of agitation as a function of the rate of increase of the melted metal.

4. The method of melting metal in a furnace which comprises heating the metal to a melting temperature, gently agitating the metal as it begins to melt, and then increasing the amount of agitation as the melting of the metal continues. 20

5. The method of melting metal in a furnace which comprises heating a quantity of metal to 25 a melting temperature, gently agitating the metal as it begins to melt, and then increasing the agitation at such rate as to substantially reach a maximum when all the metal is melted.

6. The method of melting a quantity of metal 30 in a furnace which consists in increasingly agitating the metal as a function of the time required to completely melt the metal.

7. The method of melting a quantity of metal 35 in a furnace which comprises agitating the metal during the melting operations, and increasingly varying said agitation at a rate dependent upon the time required to completely melt the metal.

8. The method of melting metal in an electrode type furnace which comprises initially subjecting the metal to rocking movements of relatively small amplitude, whereby damage to the electrode by unmelted metal striking the same is prevented, and thereafter increasing the amplitude of rocking movement, when a sufficient amount of metal 40 has melted to prevent unmelted metal striking the electrode. 45

9. The method of melting metal in a furnace which comprises agitating the melted metal to cause it to wash the unmelted metal during the 50 melting operation, and increasingly varying the amount of agitation of the melted metal, as the melting of the metal progresses, in accordance with the rate at which said metal is being melted.
